E. H. BOSTOCK,
PRECAUTIONARY SIGN.
APPLICATION FILED FEB. 15, 1916.

Patented Apr. 3, 1917.

UNITED STATES PATENT OFFICE.

EDGAR H. BOSTOCK, OF NUTLEY, NEW JERSEY, ASSIGNOR OF ONE-HALF TO MANSFIELD & CO., OF NEW YORK, N. Y., A CORPORATION OF NEW YORK.

PRECAUTIONARY SIGN.

1,221,277.

Specification of Letters Patent.

Patented Apr. 3, 1917.

Application filed February 15, 1916. Serial No. 78,412.

To all whom it may concern:

Be it known that I, EDGAR H. BOSTOCK, a citizen of the United States, and a resident of Nutley, in the county of Essex and State of New Jersey, have invented a new and Improved Precautionary Sign, of which the following is a full, clear, and exact description.

The object of the invention is to provide a new and improved precautionary sign, more specially designed for use over the exits of theaters, concert halls and other buildings and arranged to be distinctly visible in case the usual illuminating means should be extinguished for any reason whatever, thus enabling an audience to reach the exit in the dark and thereby preventing a panic in case of a fire or other disturbance. In order to produce the desired result, use is made of a sign preferably located over an exit door and provided with indicating characters defined by a light absorbing substance, to render the characters visible in the dark and illuminating means associated with the said characters to render the said characters visible as long as the illuminating means are burning and to cause the rays of light emanating from the said illuminating means to be absorbed by the substance during the time the illuminating means are burning to render the said characters visible in the dark for a considerable length of time after the said illuminating means are extinguished.

A practical embodiment of the invention is represented in the accompanying drawings, forming a part of this specification, in which similar characters of reference indicate corresponding parts in all the views.

Figure 1 is a face view of the precautionary sign with a portion of the reflector or a hood shown broken out;

Fig. 2 is a transverse section of the same on the line 2-2 of Fig. 1;

Fig. 3 is a sectional plan view of the same on the line 3-3 of Fig. 1;

Fig. 4 is an enlarged sectional plan view of a portion of the glass sign plate;

Fig. 5 is a reduced face view of a modified form of the precautionary sign with a portion of the hood broken out; and

Fig. 6 is an edge view of the same.

The frame 10 of the precautionary sign is preferably made of tin or other bright reflecting material having a back 11 and retaining flanges 12 at the bottom and the

sides. The surface of the back 11 is left in its natural state and is hence bright or shiny. The retaining flange 12 at the left-hand side of the frame is left open along the edge to allow of inserting a sign plate 13 into the frame 10, the said sign plate overlying the bright surface of the back 11. Retaining clips 14 are attached to the left-hand frame flange 12 and are bent over the edge onto the rear of the back 11 after the plate 13 is introduced into the frame 12 to hold the said plate against accidental displacement in the frame.

The sign plate 13 is made of glass or other diaphanous material and is provided on its face with recesses 15 shaped to correspond to indicating characters such as letters of the alphabet, as will be readily understood by reference to Figs. 1 and 5. Thus, the sign plate 13 shown in the drawings depicts the word "Exit." Each of the recesses 15 is filled with a light absorbing substance 16, such as luminous paint and the recess 15 is surrounded by a border 17 formed by polishing the corresponding glass surface. Adjacent the border 17 is a second auxiliary border 18 formed by producing recesses in the face of the glass plate, the back of each recess being roughened by sand blasting or similar processes. The surface of the glass plate 13 between the auxiliary recesses 18 is provided with a coating 19 of dull paint. By the arrangement described, the indicating characters of the sign are well defined so as to be plainly legible.

The upper end of the frame 10 is provided at the front with a hood or a reflector 20 open at the bottom and containing an illuminating means, preferably in the form of an electric lamp 21, which may be in the form of a plain bulb lamp, as shown in Figs. 1 and 2, or in the form of an elongated one, as indicated in Figs. 5 and 6. The lamp 21 shown in Figs. 1 and 2 has its bulb screwed into a socket 22 attached to the wall directly above the exit door of a theater and the said socket 22 extends through an opening 23 in the frame 10 to support the sign on the wall. It will be noticed that the sign is locked in position on the supporting socket 22 by the lamp bulb when screwed in place in the socket 22. In case an elongated electric lamp is used, as shown in Figs. 5 and 6, the frame is provided with an eye 25 adapted to be engaged with a hook 26 attached to the wall.

110

It will be noticed that when the electric lamp 21 is burning, it illuminates the face of the sign and consequently the indicating characters thereon are plainly visible and in case of a fire, the audience can readily find the doors, owing to the illuminated exit signs. Some of the rays of light emanating from the electric lamp 21 and directed down on to the indicating characters by the hood 20 are absorbed by the light absorbing substance 16, thus rendering the indicating characters luminous, in case the electric lamp 21 should become extinguished for any reason whatever. Thus, if the electric means within a theater fail and the lamps 21 become extinguished, then the indicating characters are rendered visible by the luminous substance used in forming the indicating characters and hence the audience can readily see the exit signs in the dark.

By providing the sign plate with the polished border 17 and the auxiliary borders 18 and covering the intermediate spaces with a dull paint 19, the sign becomes very legible during the time it is illuminated by the rays of light from the lamp 21, or during the time the sign is rendered visible by its luminous substance, especially in view of the bright surface of the metal back 11 being reflected in graded intensity by the polished border 17 and the dull border 18.

Having thus described my invention, I claim as new and desire to secure by Letters Patent:

1. In combination with an electric lamp, a sign plate, a reflector hood attached to the front upper part of the said sign plate and open at the bottom, the said hood inclosing the said electric lamp, and indicating characters on the face of the said sign plate below the said hood and defined by a light absorbing substance, the said indicating characters having polished borders surrounded by depressed dull borders and be-

ing illuminated and rendered legible by the 45 said electric lamp while the latter is burning and the rays of light emanating from the said burning lamp being absorbed by the substance to render the said characters legible in the dark after the said lamp is extinguished. 50

2. A sign, comprising a frame, the back of which has its front surface of a bright material, and a sign plate held in the frame and overlying the said bright surface, the sign 55 plate being made of glass and provided on one face with recesses defining indicating characters, the recesses having polished borders surrounded by depressed dull auxiliary borders, a coating of dull paint covering 60 the face of the glass intermediate the said auxiliary borders, and a luminous substance filling the said character indicating recesses.

3. A sign plate made of glass having recesses shaped to correspond to indicating 65 characters and filled with luminous paint and auxiliary recess adjacent the first recesses and having dull surfaces, the portions between the recesses forming a border and polished and the portions of the plate between the auxiliary recesses being coated 70 with a dull paint.

4. A sign plate formed of glass and provided with recesses shaped to correspond to indicating characters and filled with light 75 absorbing material, and with narrow recesses surrounding the first recesses and having roughened bottoms, the portions of the plate surrounding the recesses having a dull 80 surface.

In testimony whereof I have signed my name to this specification in the presence of two subscribing witnesses.

EDGAR H. BOSTOCK.
